US00D772297S

(12) **United States Design Patent** (10) Patent No.: **US D772,297 S**
Chaudhri et al. (45) Date of Patent: **** Nov. 22, 2016**

(54) **DISPLAY SCREEN OR PORTION THEREOF WITH GRAPHICAL USER INTERFACE**(71) Applicant: **Apple Inc.**, Cupertino, CA (US)(72) Inventors: **Imran Chaudhri**, San Francisco, CA (US); **Jonathan Dascola**, San Francisco, CA (US); **Alan C. Dye**, San Francisco, CA (US); **Christopher Foss**, San Francisco, CA (US); **Chance Graham**, Campbell, CA (US); **Jonathan P. Ive**, San Francisco, CA (US); **Stephen O. Lemay**, San Francisco, CA (US); **Wan Si Wan**, Sunnyvale, CA (US)(73) Assignee: **Apple Inc.**, Cupertino, CA (US)(***) Term: **15 Years**(21) Appl. No.: **29/540,972**(22) Filed: **Sep. 29, 2015****Related U.S. Application Data**

(63) Continuation of application No. 29/501,098, filed on Sep. 1, 2014.

(51) **LOC (10) Cl.** **14-04**
(52) **U.S. Cl.**USPC ..... **D14/492; D14/485**(58) **Field of Classification Search**USPC D14/485-495; 715/700-867, 961-978
CPC G06F 2203/04807; G06F 3/04817;

Primary Examiner — Cathron Brooks*Assistant Examiner* — Cary M Robinson(74) *Attorney, Agent, or Firm* — Sterne, Kessler, Goldstein & Fox P.L.L.C.(57) **CLAIM**

The ornamental design for a display screen or portion thereof with graphical user interface, as shown and described.

DESCRIPTION

The FIGURE is a front view of a display screen or portion thereof with graphical user interface showing our new design.

The outermost broken lines in the FIGURE show a display screen or portion thereof, and form no part of the claimed design. The other broken lines in the FIGURE show portions of the graphical user interface that form no part of the claimed design.
